CYLINDER HEAD CONSTRUCTION FOR
WATER-COOLED ENGINES

Fred A. Lee, Fort Wayne, Ind., assignor to International Harvester Company, a corporation of New Jersey

Application April 23, 1947, Serial No. 743,364

16 Claims. (Cl. 123—173)

1

This invention relates to a cylinder head for internal combustion engines and the like and more particularly to a cylinder head of the fabricated light-weight sheet metal type.

The advantages of fabricated cylinder heads and similar engine components are well known. It is also well known that these advantages cannot always be easily and inexpensively achieved. In the design and construction of fabricated cylinder heads, for example, various problems must be taken into consideration and it has heretofore been rather difficult to eliminate all these problems and provide a satisfactory structure.

A principal object of the present invention is to provide an improved fabricated cylinder head in which the component parts are fabricated as units to as great an extent as possible and then assembled to complete the head. An important object is to provide the main structure of the head as a plurality of plates assembled to provide generally a box-like structure. Other objects are to provide suitable openings in the plates to accommodate individual combustion chambers, valve openings, spark plug openings, and exhaust and intake openings and ports therefor in connection with the combustion chambers. Still another object is to construct the cylinder head in such a manner that it may be readily connected to the coolant circulating system of certain conventional types of internal combustion engines.

The foregoing and other important objects will appear in greater detail in the following description, taken in conjunction with the accompanying sheets of drawings, in which:

Figure 1 is a plan view of a preferred form of fabricated cylinder head.

Figure 2 is a side elevational view of the cylinder head as viewed along the line 2—2 of Figure 1.

Figure 3 is a side view taken from the other side of the head, as indicated by the line 3—3 of Figure 1.

Figure 4 is an end elevation taken of one end of the head as viewed along the line 4—4 of Figure 1.

Figure 5 is an end view of the other end of the head as viewed along the line 5—5 of Figure 1.

Figure 6 is a transverse sectional view through the head taken on the line 6—6 of Figure 1.

Figure 7 is a fragmentary longitudinal sectional view through the head taken on the line 7—7 of Figure 1.

Figure 8 is a fragmentary horizontal sectional view, on an enlarged scale, taken on the line 8—8 of Figure 6.

Figure 9 is a fragmentary view taken on the

line 9—9 of Figure 8 and showing one of the Siamese manifold ports.

Figure 10 is an enlarged exploded view showing the components in end elevation that make up the head structure.

The cylinder head chosen for the purposes of illustration comprises a bottom or base plate 20, of generally rectangular shape, having one longitudinal edge thereof bent upwardly to form a longitudinal vertical side wall or plate 21. The upper edge of the plate 21 is rigidly secured by welding or brazing, as indicated at 22, to a generally rectangular upper or top plate 23. The plates 20 and 23 are preferably parallel and are spaced vertically apart at one edge of the head structure by the side wall 21 and at the other side of the head by a plurality of vertical tubular spacers 24, additional spacers 25 being provided in longitudinally spaced relation adjacent the side wall 21 (Figures 6 and 8). The ends of the head structure are closed by opposite end walls 26 (Figures 3, 4 and 7) and 27 (Figures 3 and 5). The bottom plate 20 is provided with a plurality of longitudinally aligned circular openings 28 (Figures 8 and 10), within each of which is mounted a combustion chamber 29. The combustion chamber is generally in the form of an inverted cup having a circular radial wall 30 and an integral annular wall 31. The wall 31 fits within the opening 28 in the bottom plate 20 and the combustion chamber is welded to the plate 20 around the circular junction between the circular wall 31 and the plate, as indicated at 32.

The circular radial wall of each combustion chamber 29 is pressed outwardly to provide a portion 33 apertured at 34 to receive a collar 35 (Figure 10). The collar includes a sleeve portion 36 that fits the aperture 34 in the portion 33, and the collar is welded or brazed to the portion 33. The collar includes an axial threaded bore 37 (Figure 6) adapted to receive a spark plug (not shown). The collar is additionally provided with a coaxial sleeve 38 formed with a counterbore 39.

A longitudinally extending side plate 40 is carried at the side of the head opposite the side wall 21. This plate 40 is provided at longitudinally spaced points thereof with inwardly formed portions 41, each of which is apertured at 42 to receive the reduced sleeve 38 on the collar 35. The upper and lower edges of the plate 40 are flanged at 43 and 44, respectively, and are welded or brazed, respectively, to the under surface of the upper plate 23 and the upper surface of the base plate 20. The opposite ends of the side plate 40 include integral end flanges 45 welded or brazed

2

40

45

50

at 46 to the end plates 26 and 27. A ring 47 is interposed between each collar 35 and proximate depressed portion 41 of the side plate 40. A second ring 48 fits over that portion of the reduced sleeve 38 that extends outwardly through the opening 42 in the portion 41 of the plate 40. The surplus portion of each sleeve 38 that projects outwardly beyond the ring 48 is spun or flanged over the ring and is further welded or brazed to secure the plate 40 to the collars 35, as at 49 (Figures 6 and 8).

Each combustion chamber 29 is provided in its radial wall portion 30 with a pair of valve openings 50 and 51 (Figures 7 and 8). The openings 50 and 51 will be referred to as the exhaust and intake openings respectively. It will be noted that these openings are reversed in successive combustion chambers (Figure 8) so that the openings 51 are closely adjacent, the purpose of which will presently appear. Each exhaust opening 50 is fitted with an exhaust port 52, the inner end portion of which includes an elbow having an integral collar 53 which fits a ring 53^a which in turn fits the opening 50 in the combustion chamber (Figure 7). A circular valve seat or ring 54 also fits the ring 53^a (Figure 7) and is, of course, coaxial with the collar 53 on the exhaust port elbow. The exhaust port is preferably formed of upper and lower halves welded or brazed together as at 55 (Figures 6 and 7) to form the complete port assembly.

The side plate 21 is provided with a plurality of longitudinally spaced openings 56 (Figure 2) which respectively receive the outer ends of the exhaust ports 52, the connections between the plate 21 and the ports 52 being accomplished by welding or brazing. The plate 21 is further provided with tapped bores 57 adjacent each opening 56. These bores are provided for receiving cap screws, by means of which an exhaust manifold (not shown) may be attached to the head structure.

Each exhaust port 52 includes in its upper wall a vertical opening 58, within which is carried the lower end of a vertical tubular member 59. The upper plate 23 is provided with a plurality of openings 60 which receive the upper ends of the members 59 (Figure 7). The member 59 is welded or brazed at its opposite ends to the plate 23 and exhaust port 52 as at 61 and 62, respectively. The welding or brazing operation by which the joint is accomplished between each member 59 and exhaust port 52 is performed before the exhaust port is assembled in place in the head structure and is preferably performed as one of a series of operations by which the combustion chambers 29 are assembled to their associated exhaust and intake ports, the latter of which will be described presently.

The members 59 serve, first, as tubular spacers between the exhaust ports 52 and plate 23 and, second, as means for carrying valve guides 63. The valve guides are, of course, coaxial with the valve seats 54.

The intake opening 51 in each of a pair of adjacent combustion chambers 29 is fitted with a ring 64 (Figures 7 and 10), and each ring receives a collar portion 65 formed as an integral part of a Siamese intake port indicated generally by the numeral 66. The port 66 preferably comprises upper and lower halves welded or brazed together along the line indicated at 67 (Figure 7) to complete the port. That portion of the Siamese port 66 that extends at a right angle to the portion including the collars 65 communicates with an

opening 68 in the side wall 21 of the head structure, it being understood that there are three such openings 68 for three Siamese ports 66 to accommodate six intake valve openings 51. The plate 21 is provided with a pair of tapped bores 69 adjacent each intake opening 68, for the purpose of receiving cap screws, by means of which an intake manifold (not shown) may be attached to the head structure. The upper portion of each intake port 66 is provided with a pair of spaced openings 70, each of which receives the lower end of a vertical tubular spacer 71. The upper end of each spacer is carried in an opening 72 formed in the upper plate 23 coaxial with the opening 15 70 in the intake port 66. The spacers are welded or brazed as at 73 to the intake ports 66, this operation being preferably performed in a series of operations that includes the assembling of the ports before installation in the head structure. 20 Subsequently the upper ends of the sleeves 71 are welded or brazed to the upper plate 23. Each sleeve 71 carries therein a vertical valve guide 74. The valve guides 74 like the valve guides 73 are preferably formed of upper and lower coaxial sections 25 (Figures 7 and 10).

The rings 64, which receive the collars 65 of the intake ports 66 and which fit the intake openings 51 in the combustion chambers 29, also carry circular valve seats or rings 75 (Figure 7).

30 A plurality of pairs of tubular members 76 extend vertically from the base plate 20 upwardly through the upper plate 23 to a short distance above the upper plate. These members 76 are rigidly secured, as by welding or brazing, to the 35 upper and lower plates, and the upper extensions thereof serve to carry rocker arm structure (not shown) for operating valves (not shown) carried in the valve guides 63 and 74. The upper plate 23 is provided at one corner thereof with a rectangular opening 77 bordered with a machined surface 78 having a pair of tapped bores 79, by means of which a coolant-circulating connection (not shown) may be made. The end wall 26 is provided with a similar opening 80 and tapped bores 81, for the purpose of accomplishing a similar connection.

50 The tapped bores 57 and 69 adjacent the exhaust and intake openings 56 and 68, respectively, in the side wall 21 of the head structure are reinforced by a plurality of members 82 (Figures 8 and 10), each of which includes a tapped bore coincident with its proximate tapped bore in the side wall 21.

55 In the assembly of the head structure it is preferable to preassemble various units. For example, it is desirable to place the combustion chambers 29 in position in the openings 28 of the bottom plate 20, suitable jigs being utilized to position these elements properly. The exhaust and intake ports, being in two halves, are preferably preassembled and then assembled to the combustion chambers, positioning of the rings 53^a and 64 and valve seats 54 and 75 being accomplished at the same time. The spacers 24 and 25 and the vertical tubes 76 may then be assembled to the bottom plate 20, and the tubular members 59 and 71 and valve guides 63 and 74 may then be assembled to the ports 52 and 66, after which the upper plate 23 may be located, assembled and secured by welding or brazing. This operation may be followed by installation of the side plate 40, the collars 35 having been previously assembled to the combustion chambers 29. However, the procedure by which the head structure is assembled may be varied at will, depend-

ing upon planning and equipment. It is essential, of course, that the joints accomplished by welding or brazing between the components be fluid-tight.

The disclosure as set forth herein is, of course, directed to a preferred embodiment of the invention, and the exact details of construction illustrated and described should not be taken as delineating the applicability of the invention, for numerous modifications and alterations may be made in this preferred structure without departing from the spirit and scope of the invention as set forth in the appended claims.

What is claimed is:

1. A fabricated cylinder head for an internal combustion engine, comprising: a generally flat horizontal bottom plate of rectangular shape having one longitudinal edge thereof bent up to provide a longitudinal side wall; means providing a plurality of circular openings in the bottom plate; a plurality of combustion chamber elements, each including an inverted cup, respectively fitting the circular openings and rigidly secured to the plate; means providing a pair of valve openings in each combustion chamber element; means providing a plurality of longitudinally spaced intake and exhaust openings in the side wall; means including intake ports rigidly secured to the side wall and to the combustion chamber elements and connecting the intake openings with one of the pair of valve openings in each combustion chamber element; and means including exhaust ports rigidly secured to the side wall and to the combustion chambers and connecting the exhaust openings with the other of the pair of valve openings in each combustion chamber element.

2. A fabricated cylinder head as set forth in claim 1, further characterized in that: a generally flat upper plate is spaced vertically above the bottom plate and is rigidly joined to an upper edge portion of the side wall; and vertical spacers are rigidly secured at opposite ends to the bottom and upper plates.

3. A fabricated cylinder head as set forth in claim 2, further characterized in that: additional vertical spacers in the form of tubular elements are rigidly secured at opposite ends to the upper plate and to the combustion chamber elements coaxially with the valve openings therein; and means are carried by the vertical tubular elements and serve as valve guides.

4. A fabricated cylinder head as set forth in claim 1, further characterized in that: each combustion chamber element includes a spark plug opening having its axis directed away from the side wall; an upper plate of size and shape generally similar to the bottom plate is spaced vertically above and parallel to the bottom plate; means rigidly joins one longitudinal edge of the upper plate to an upper edge portion of the side wall; and a side plate provided vertically between the upper and bottom plates at the sides thereof opposite the side wall, said side plate having its upper and lower edge portions respectively rigidly joined to the upper and bottom plates, said side plate further including a plurality of openings coinciding with the spark plug openings.

5. A fabricated cylinder head as set forth in claim 4, further characterized in that: all the aforesaid joints between the parts of the assembly are water-tight; end plates are provided at opposite ends of the assembly and are rigidly secured to the side wall and to the upper bottom and side plates to provide a water-tight joint; and means including a water-tight joint is provided

between the side plate and each combustion chamber surrounding the juncture of each spark plug opening and associated side plate opening.

6. A fabricated cylinder head as set forth in claim 5, further characterized in that: the upper plate and one of the end plates are each provided with a coolant opening, one of the openings being an inlet opening and the other an outlet opening for connection to a coolant system.

7. A fabricated cylinder head for an internal combustion engine, comprising: a lightweight, sheet metal, generally horizontal bottom plate; means providing a lightweight, sheet metal side wall rigidly joined to the plate; means providing a circular opening in the bottom plate; a combustion chamber element including an inverted cup fitting the circular opening and rigidly secured to the plate; means providing a pair of valve openings in the combustion chamber element; means providing intake and exhaust openings in the side wall; and means including intake and exhaust ports rigidly secured to the side wall and to the combustion chamber element and connecting the intake and exhaust openings with the valve openings in the combustion chamber elements.

8. A combustion chamber for a fabricated, lightweight cylinder head, comprising: a lightweight sheet metal element shaped as an inverted cup having a generally circular radial wall portion and an integral depending annular flange; means forming a pair of valve openings in the radial wall portion; and means in the radial wall portion including an outwardly pressed portion having an opening therethrough in communication with the interior of the chamber and adapted to receive a spark plug or the like.

9. In a fabricated, lightweight cylinder head, the combination of: a base plate; means providing an opening in the base plate; a lightweight sheet metal combustion chamber having a radial wall portion and an integral peripheral flange, the latter fitting the opening in the base plate and being rigidly secured to the base plate; means in the radial wall portion providing an opening therethrough; an upstanding side plate rigidly joined to the base plate and having an opening therein aligned with the opening in the combustion chamber; a cup-shaped member fitting the side plate opening and having an opening in its bottom coincident with the opening in the combustion chamber, the bottom of the cup-shaped member being rigidly secured to the combustion chamber around the opening therein; and means providing a flange on the cup rigidly secured to the side plate around the opening therein.

10. A fabricated, lightweight, sheet metal cylinder head, comprising: a base plate, a top plate, opposed end plates and opposed side plates, each of generally flat, rectangular shape and all rigidly secured together to provide a box-like structure; means providing a row of openings in the bottom plate; means providing a row of openings in one of the side plates; and a plurality of separate combustion chambers respectively fitting said bottom plate openings and secured to the bottom plate and including ports in communication with the side plate openings and secured to said side plate.

11. A cylinder head as set forth in claim 10, further characterized in that: the opposite side plate includes a plurality of spark plug openings, one for each combustion chamber; and the combustion chambers each include a spark plug

opening respectively aligned with the spark plug openings in the side plate.

12. A cylinder head as set forth in claim 10, further characterized in that: the bottom and top plates are separated by a plurality of spacers, certain of which include a set of vertical tubes providing openings through the structure for receiving studs or the like to secure the head to an engine block.

13. A cylinder head as set forth in claim 12, further characterized in that: certain of the vertical tubes extend upwardly beyond the top plate and serve to receive engine components.

14. A cylinder head as set forth in claim 13, further characterized in that: certain of the first set of vertical tubes extend upwardly beyond the top plate and serve to carry valve-operating mechanism.

15. A fabricated, lightweight, sheet metal cylinder head, comprising: a base plate, a top plate, opposed end plates and opposed side plates, each of generally flat, rectangular shape and all rigidly secured together to provide a box-like structure; the base and top plates being separated by a plurality of spacers, certain of which include a set of vertical tubes providing openings through the structure for receiving studs and the like to secure the head to an engine block; means providing a row of openings in the bottom plate; means providing a row of openings in one of the side plates; a plurality of separate combustion chambers respectively fitting said bottom plate openings and secured to the bottom plate and including ports in communication with the side plate openings and secured to said side plates; each combustion chamber being provided with a pair of valve openings; the top plate being provided with openings respectively aligned with the valve openings; and a second set of vertical tubes

extending between the combustion chambers and the top plate respectively coaxial with the valve openings and the openings in the top plate.

16. A combustion chamber and valve port assembly for a fabricated, lightweight cylinder head, comprising: a lightweight, sheet metal combustion chamber having the shape of an inverted cup and including a generally circular radial wall portion and an integral annular flange; means providing a circular valve opening in the radial wall portion; and a valve port including a generally tubular portion fitted within the valve opening and rigidly secured to the radial wall portion; said valve portion being additionally provided with a tubular elbow portion that projects away from the combustion chamber; and having said elbow formed as an element split along the axis of the projecting tubular portion, the split parts being welded together to provide the unitary elbow.
